Patented Apr. 29, 1958

182,652

TRAVELING WAVE TUBE UNIT

Wilson S. Geisler, Jr., Atherton, Calif.

Application February 23, 1955, Serial No. 34,625

Term of patent 14 years

(Cl. D26—1)

FIG. 1

FIG. 2

FIG. 3

Fig. 1 is a perspective view of the traveling wave tube unit showing my new design.

Fig. 2 is an end elevational view thereof, and

Fig. 3 is a side elevational view of the unit.

I claim:

The ornamental design for a traveling wave tube unit, as shown.
